UNITED STATES PATENT OFFICE.

JOHN STOW ANDERSON, OF CORSICANA, TEXAS.

FEED-TROUGH.

SPECIFICATION forming part of Letters Patent No. 472,971, dated April 19, 1892.

Application filed September 5, 1891. Serial No. 404,841. (No model.)

To all whom it may concern:

Be it known that I, JOHN STOW ANDERSON, a citizen of the United States, residing at Corsicana, in the county of Navarro and State of Texas, have invented a new and useful Feed-Trough, of which the following is a specification.

The invention relates to improvements in portable feed racks and troughs.

10 The object of the present invention is to provide a portable feed rack and trough adapted to hold a quantity of feed and to discharge the same as is found necessary.

15 The invention consists in the construction and novel combination and arrangement of parts hereinafter fully described, illustrated in the accompanying drawings, and pointed out in the claim hereto appended.

20 In the drawings, Figure 1 is a perspective view of a portable feed rack and trough embodying the invention. Fig. 2 is a vertical longitudinal sectional view. Fig. 3 is a transverse sectional view. Fig. 4 is a detail sectional view. Fig. 5 is a detail perspective 25 view of a portion of the hay-rack.

Referring to the accompanying drawings, 1 designates a platform, which is provided at each side with a feed-trough 2 and which is mounted upon runners 3, so as to be portable; but it will be readily understood that wheels may be substituted for runners.

Arranged at each end of the platform is a tapering bin or hopper 4, having inwardly-inclined sides 5 and provided at the lower 35 ends of the sides with discharge-openings 6, opposite which are arranged adjustable slides 7, adapted to regulate the sides of the openings. The slides 7 are secured in their adjustment by set-screws 8 and are held in 40 frictional contact with the inclined bars 9, which are arranged on the outer faces of the sides 5 and are recessed at their lower ends, and arranged on the outer edges of the bars 9 are strips 10, which are also held in frictional contact with the bars 9 by the said set-screws 8. The bins or hoppers may be entirely closed at their sides by hinged doors 11, closing against triangular pieces 12, arranged at the sides of the bins or hoppers 45 and forming a straight vertical jamb. The outer end walls 13 of the hoppers or bins are

provided with doors 14, by which the hoppers or bins are supplied with feed.

A feed-rack 15 is arranged between the hoppers or bins, and its sides 16 are composed of slats and are provided at their lower ends with openings and sliding doors 17, arranged to close or partially close the openings.

The bins and the hay-rack are provided with a sheet-metal roof 18, having at its sides 60 eaves-troughs 19 and provided with a sliding section 20, arranged over the feed-rack, whereby the same is filled.

It will be seen that a simple and comparatively inexpensive feed trough and rack 65 which is capable of holding feed within easy reach of stock is produced.

The sliding doors 17 are composed of bars 21, which are arranged at intervals and are located in the spaces formed by the slats 22 70 of the feed-rack 15. These slats serve as guides for the sliding doors and have their lower ends connected by cross-bars 23, and the bars 21 of the sliding doors are connected at their ends by horizontal strips 24, which 75 are arranged on the outer faces of the slats 22 and secure the doors to the rack. The upper horizontal strip rests upon the cross-bar 23 when the door is closed, and the lower horizontal strip limits the upward movement 80 of the doors. When the doors are open or raised, they fill and close the spaces between the slats at the point within the reach of animals and prevent the same pulling hay through the spaces formed by the slats and 85 compel them to eat out of the trough and draw the hay through the doors.

Any suitable means may be provided for holding the doors open in their adjustment.

Each bin has extending longitudinally of it and arranged a short distance above the lower edges of its sides a bar 26, which is triangular in cross-section and is adapted to support the weight of the feed and prevent the same exerting great pressure against the 95 adjustable slides 7.

What I claim is—

A combined feed rack and trough comprising a platform mounted on runners and provided at its sides with troughs, bins arranged 100 at the ends of the platform and provided at the lower ends of their sides with openings

communicating with the troughs and having bars arranged on the outer faces of the sides and provided with recesses, slides arranged in said recesses and adapted to vary the size of said openings, strips arranged on the outer edges of the inclined bars, and set-screws connecting the strips and the slides and holding the same in frictional contact with the bars, whereby the slides are secured in their ⁵ adjustment, and the hinged doors arranged

at the sides of the bins, substantially as described.

In testimony that I claim the foregoing as my own I have hereto affixed my signature in presence of two witnesses.

JOHN STOW ANDERSON.

Witnesses:

J. J. WILSON,
M. B. CHILCOOT.
